(57) **CLAIM**

The ornamental design for a pet toy as shown and described.

DESCRIPTION

FIG. 1 is a top perspective view of the pet toy.

FIG. 2 is a front elevation view of the pet toy, the other elevation views being the same.

FIG. 3 is a top plan view of the pet toy.

FIG. 4 is a bottom plan view of the pet toy; and,

FIG. 5 is a section view of the pet toy taken along line 5-5 of FIG. 3.

The dash-dot lines in the drawings define the boundary of the claimed design and form no part thereof. The regular dashed lines in the drawings illustrate portions of the pet toy forming no part of the claimed design.
